(57) **CLAIM**

The ornamental design for a loader fender, as shown and described.

DESCRIPTION

FIG. 1 is a front left side perspective view of a loader fender showing our new design.

FIG. 2 is a top view of the loader fender design of FIG. 1.

FIG. 3 is a right side view of the loader fender design of FIG. 1.

FIG. 4 is a left side view of the loader fender design of FIG. 1.

FIG. 5 is a front view of the loader fender design of FIG. 1; and,

FIG. 6 is a rear view of the loader fender design of Figure 1.

The broken line showing of a tractor is included for the purpose of illustrating environmental structure and forms no part of the claimed design.

1 Claim, 6 Drawing Sheets
